Primary Examiner — Susan E Krakower*Assistant Examiner* — Camelia Styles(74) *Attorney, Agent, or Firm* — Fitzpatrick, Cella, Harper & Scinto**CLAIM**

The ornamental design for a shingle, as shown and described.

DESCRIPTION

FIG. 1 is a top plan view of a shingle showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a perspective view thereof; and,

FIG. 7 is a bottom plan view thereof.
